(57) **CLAIM**

The ornamental design for a combined paper cutting and trimming apparatus and decorative-edged cutting shears, as shown and described.

DESCRIPTION

FIG. 1 is a top, front perspective view of a combined paper cutting and trimming apparatus and decorative-edged cutting shears showing our new design;

FIG. 2 is a left side elevation thereof;

FIG. 3 is a bottom plan view thereof;

FIG. 4 is a right side elevation thereof;

FIG. 5 is a top plan view thereof;

FIG. 6 is a rear elevation thereof;

FIG. 7 is a front elevation thereof;

FIG. 8 is a perspective view of one of the decorative-edged cutting shears members shown separately and removed from the paper cutting and trimming apparatus;

FIG. 9 is a top plan view thereof; and,

FIG. 10 is a top plan view of the alternate decoration edged-cutting shears member.
